UNITED STATES PATENT OFFICE.

HUGH M. FERGUSON, OF PORT HURON, MICHIGAN.

AIR PREHEATER FOR FURNACES.

Application filed October 1, 1923, Serial No. 665,778. Renewed November 6, 1926.

This invention relates to means for directing a wide jet or blast of very hot air into the zone of combustion just above the upper surface of the burning coal or other fuel in the fire-pot or on the grate of a furnace in order to accelerate and complete the combustion of the fuel, and its object is to provide a device of this character which can be attached to the fire-door of substantially every type of furnace at low cost.

This invention consists in a nozzle adapted to be attached to the inside of the fire-door or other convenient part of a furnace and provided with projections such as fins on its outer surface to receive the radiant heat of the fire and with projections on its inner surface to transmit this heat to the air passing through the nozzle to the fire.

It further consists of the details of construction illustrated in the accompanying drawing and particularly pointed out in the claim.

In the drawing, Fig. 1 is an elevation of this improved air nozzle attached to a fire-door, the furnace being broken away to show the manner of mounting the nozzle. Figs. 2, 3 and 4 are sections on the lines 2-2, 3-3 and 4-4 of Fig. 1 respectively.

Similar reference characters refer to like parts throughout the several views.

The fires of boilers and other furnaces often smoke and are otherwise inefficient because of an insufficient supply of air, the fuel being only partially consumed. This is particularly true in the hot air furnaces used for heating dwellings, which, because of the unskilled attendance, are peculiarly liable to smoke. I have found that this smoking can be practically prevented by directing a blast or current of air into the very hot gases that rise from the bed of burning coal on the grate of the furnace by means of a nozzle embodying the present invention.

In the drawing, the furnace 1 is shown equipped with a fuel chute 2 closed by means of a door 3 which is hinged in any desired manner. The nozzle 4 is shown secured to this door by means of the screws 5 passing through the flange 6. The nozzle preferably inclines downwardly toward the fuel 7 in the fire-pot and the flow of air through the nozzle may be regulated by a disk 8 mounted on a screw 9. This disk may be moved toward and from the door to regulate the flow of air through the openings 10 in the door.

I prefer the upper wall 12 and lower wall 13 of the nozzle to approach each other while the side walls 14 separate toward the inner end of the nozzle so as to flatten the blast of air passing to the flame above the fuel. Fins or ribs 16 are attached to the upper and lower walls and extend inwardly so as to divide the interior of the nozzle into narrow channels. Transverse fins or ribs 15 are attached to the outer surface of the nozzle and receive a portion of the radiant heat of the fuel, thus heating the walls of the nozzle and the fins or ribs 16 on the inside thereof.

As the air rushes into the furnace through the nozzle because of the draught of the furnace, it will be highly heated by the fins 16, and as it is directed directly into the zone of combustion above the fuel on the grates, it will mingle with the burning gases and cause more intense and complete combustion of the fuel. By forming the discharge end of the nozzle quite wide, the blast of hot air may be spread out to the width of the fuel on the grate. I have found that the transverse arrangement of the external fins or ribs is very effective for intercepting and absorbing the heat radiated by the burning fuel for the purpose of obtaining the heat necessary to bring the incoming air to a high temperature, which results in the complete combustion of the gasified fuel. It should be understood that the nozzle may be attached to any other convenient part of the furnace.

The details and proportions of the various parts of this nozzle may be changed by those skilled in the art to adapt it to the different types and sizes of furnaces, without departing from the spirit of my invention as set forth in the following claim.

I claim:

In a furnace having a combustion chamber, a nozzle extending downwardly from an apertured portion of the furnace toward the zone of combustion, said nozzle having longitudinal interior ribs and transverse external ribs extending around the nozzle, the top and bottom of the nozzle approaching and the sides separating toward the discharge end so as to deliver a wide blast of air to the zone of combustion.

HUGH M. FERGUSON.
